CLAIM

The ornamental design for a multi-purpose hand tool, as shown and described.

DESCRIPTION

FIG. 1 is a top plan view of a multi-purpose hand tool embodying my new design, with the handles in the folded position, wherein screwdrivers attached to the handles are illustrated in an extended position in phantom and form no part of the claimed design;

FIG. 2 is a bottom plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view of the multi-purpose hand tool with the handles in the folded open position;

FIG. 8 is a bottom plan view thereof;

FIG. 9 is a left side elevational view thereof;

FIG. 10 is a right side elevational view thereof;

FIG. 11 is front elevational view thereof; and,

FIG. 12 is a rear elevational view thereof.
